PRINTING METHOD AND APPARATUS

Irving F. Niles, Lakewood, Ohio, assignor to The Impress Company, Inc., Rochester, N. Y., a corporation of New York

Application June 25, 1936, Serial No. 87,243

19 Claims. (Cl. 101—186)

This invention relates to a method of printing, and to an apparatus for printing.

An object of the invention is the provision of an improved method of printing, and particularly 5 a method according to which printing may be accomplished in a plurality of different inks.

Another object of the invention is the provision of improved and simplified apparatus for printing in accordance with the method.

10 Still another object is the provision of a method and of an apparatus for printing the same printed matter a plurality of times on the same sheet of stock, with the use of a plurality of different inks.

15 A further object of the invention is the provision of printing apparatus which will, as an integral part of its operation, crease the sheets of stock in such manner as to form a hinge joint which is useful when the sheets are later bound 20 into a book or the like.

25 A still further object is the provision of a method and of an apparatus which are particularly adapted to and useful in printing checks, drafts and similar forms, although capable also of many other uses.

To these and other ends the invention resides in certain improvements and combinations of parts, all as will be hereinafter more fully described, the novel features being pointed out in 30 the claims at the end of the specification.

In the drawings:

Fig. 1 is a side view of printing apparatus constructed in accordance with a preferred embodiment of the invention;

35 Fig. 2 is a vertical section taken substantially on the line 2—2 of Fig. 1;

Fig. 3 is a horizontal section taken substantially on the line 3—3 of Fig. 1;

40 Fig. 4 is a vertical section taken longitudinally through the machine, substantially on the line 4—4 of Fig. 2;

Fig. 5 is a view of the impression cylinder and the associated paper stripping mechanism with the stripping mechanism in an ineffective position;

45 Fig. 6 is a view similar to Fig. 5 with the stripping mechanism in an effective position, and in the act of stripping a sheet from the cylinder;

Fig. 7 is a longitudinal view through the impression cylinder, with parts in section and parts broken away, and showing the paper holding dogs in normal holding position;

50 Fig. 8 is a view similar to Fig. 7 showing the paper holding dogs in open position for releasing a sheet or receiving a new sheet;

Fig. 9 is a section taken substantially on the line 9—9 of Fig. 7;

Fig. 10 is a section taken substantially on the line 10—10 of Fig. 7;

Fig. 11 is a section taken substantially on the line 11—11 of Fig. 7;

Fig. 12 is a fragmentary section taken substantially on the line 12—12 of Fig. 7;

Fig. 13 is a view partly in elevation, and partly in vertical section, of the mechanism for creasing the sheets;

Fig. 14 is another view partly in elevation, and partly in vertical section, of the paper creasing mechanism, the section being at right angles to that of Fig. 13, and being substantially on the lines 14—14 of Figs. 1 and 13;

Fig. 15 is a view similar to a fragment of Fig. 14 showing the creasing member moved upwardly to bend the sheet in one direction;

Fig. 16 is a similar view showing the creasing member moved downwardly to bend the sheet in the opposite direction;

Figs. 17 to 22, inclusive, are diagrammatic views illustrating successive positions of the printing apparatus during one cycle of movement of the printing element or type carrying element;

Fig. 23 is a view of a sheet of stock adapted to be printed on this printing apparatus, showing it as it appears at the end of one cycle of movement of the printing element;

Fig. 24 is a similar view showing the sheet as it appears at the end of the second cycle of operation of the printing element, and

Fig. 25 is a similar view showing the completed sheet as it appears at the end of the third cycle of the printing element.

The same reference numerals throughout the several views indicate the same parts.

The novel method of the present invention comprises, in general, applying the same sheet 40 of stock (such as paper) to the same printing element a plurality of times in a plurality of different portions with respect to the printing element so that each time the sheet is applied to the printing element, the printing element will 45 print on a different portion or area of the sheet. The method further comprises the steps of inking a portion of the printing element with one ink and inking another portion of the printing element with a different ink. The portion of the printing element inked with one ink may print upon one area of the sheet of stock, while the portion of the printing element inked with the different ink may print upon a different area of the sheet of stock. Then, upon one or more 50

55

subsequent applications of the sheet to the printing element, the differently inked portion of the printing element may print upon that area of the sheet which was previously printed upon by the 5 other inked portion of the printing element, and so on.

The method above outlined in general is particularly suitable and advantageous for printing checks, drafts, and similar forms, where several 10 identical or substantially identical forms are to be printed on the same sheet, but it is obvious that the method is applicable also to many other things to be printed, and is not to be construed as limited to the printing of checks, or the like, 15 which are selected merely as a convenient example for illustrative purposes.

Checks or drafts for commercial use are customarily printed three to each page of the check book, the page also having corresponding stub 20 portions from which the checks may be detached. According to the present improved method of printing, the printing element carries a printing portion or a type portion for printing certain matter on the check and stub in one ink, and another printing portion or a type portion for printing certain matter on the check and stub in a different ink. These portions having been 25 separately inked, the sheet is then applied to the type element in such position that one type portion 30 will print upon the area of one check and stub, and the other differently inked type portion will print upon the area of another check and stub. Then the type element is again inked as before, and the sheet is again applied to the type element in a different position relatively thereto, so 35 that the type portion inked with the first ink will print on one check and stub area, different from the one previously printed upon by this ink, and the type portion inked with the second ink 40 will print upon one check and stub area of the sheet, which is different from the one previously printed upon by the same ink, but which may be the same check and stub area as the one previously printed upon by the first ink. Then the 45 printing element is again reinked as before, and the sheet is applied to the printing element for a third time in still a different position so that the first inked printing portion will print upon the check and stub area which has not yet been 50 printed upon by this ink (although this same area may have been already printed upon by the other ink) and the second inked portion of the printing element will print upon the check and stub area of the sheet which has not yet been printed upon 55 by the second ink (although this portion may have been previously printed upon by the other ink). Thus, at the end of the three applications of the sheet to the printing element, all three of the check and stub areas will have been printed in 60 both of the two different inks.

Frequently, the two different inks may be inks of different colors. For example, one of them may be black and the other may be red, the name of the bank and the number of the check being 65 printed, for example, in red, while the other printed matter on the check and stub may be printed, for example, in black. Red and black inks are mentioned only as a convenient illustrative example, however, and it is to be understood that the invention is not limited necessarily to these colors, or to any particular kinds or types of ink. Obviously, if desired, one of the inks may be a visible ink and may be used to print all of the visible matter on each check and stub, while the other or different ink may be an 75

invisible ink and may be used to print on each check suitable warning indicia or the like, which will be developed and become visible when ink eradicator is applied to the check. Or again, both of the dissimilar inks may be invisible inks, when 5 it is desired to print certain matter on each check in one kind of an invisible ink and certain other matter on each check in another kind of an invisible ink. It is, therefore, within the scope of the present invention to employ different inks of 10 any desired kind or character, not necessarily visible inks of two different colors.

Another feature of the method constituting part of the present invention is that, in accordance with this method, each sheet is creased by 15 the apparatus to make an easily flexible joint along a line near one edge of the sheet, so that when the sheets are later bound into a book or the like (such as a check book), the sheets will bend easily along the previously creased lines, so 20 that the book may be readily opened up flat.

Various other features of the present method, and additional details of the features above described, will be apparent from the following description of a preferred form of printing apparatus made according to the present invention and capable of carrying out the method of the present invention.

The preferred embodiment of the apparatus comprises a main frame indicated in general by 30 the numeral 41 and having substantially vertically arranged guide rails 42 along which a bed 43 is vertically slidable. The bed 43 may have wear plates 44 on its rear surface for sliding over the rails 42, and may be held against forward move- 35 ment away from the rails by means of plates 45 secured to the bed 43 and extending around to the rear side of certain flanges on the central rails 42, as best shown in Fig. 3.

This bed 43 is provided near the bottom edge 40 of its front surface with lugs 50 on which the lower edge of a chase 51 may rest, and which are inclined so as to hold the lower edge of the chase securely in place. The upper edge of the chase may be held by a clamp 52 vertically slid- 45 able on the bed 43 and normally urged downwardly into clamping position by a spring 53. To release the chase 51, the clamp 52 may be raised by a partial rotation of the crank handle 54 which is connected to an eccentric 55 operat- 50 ing upon the clamp.

The chase carries printing types or a printing plate 57, constituting one printing portion, and also printing types or a printing plate 58, constituting another printing portion. These two 55 printing portions may be arranged closely adjacent each other, so as to print upon contiguous areas of the sheet of stock to be printed, but preferably the two printing portions are spaced from each other by a distance equal to one dimension of one or more intervening areas to be 60 printed.

In other words, if the printing portion 57 prints upon one area, the other printing portion 58 preferably does not print upon the next adjacent 65 area, but rather upon the second area from the one printed upon by the portion 57, or upon an area even further removed from the area printed upon by the portion 57 than the second area from the portion 57.

The printing portion 57 is inked by suitable inking mechanism of conventional construction indicated in general at 61, mounted on a carriage 62 movable toward and away from the type by rotation of a pinion 63 mounted on the carriage 75

and meshing with a fixed rack 64, the rotation of the pinion being controlled by a handle 65. Similarly, the other printing portion 58 is inked by inking mechanism 68 of conventional form, mounted on a carriage 69 whose movements are controlled by a pinion 70 meshing with a rack 71, the pinion being turned by a handle 72. The printing portion 57 is inked by the inking mechanism 61 near the upper end of the vertical movement of the bed 43, and does not cooperate with the other inking mechanism 68. The printing portion 58 is inked by the mechanism 68 near the lower end of the vertical movement of the bed, and does not cooperate with the other inking mechanism 61. Thus each inking mechanism inks only its cooperating printing portion, and different inks may be supplied to the two inking mechanisms, so that the two printing portions will print with two different inks. In the illustrative case selected as an example, the inking mechanism 61 inks the printing portion 57 with black ink while the inking mechanism 68 inks the printing portion 58 with red ink, but entirely different kinds of ink could be employed as above mentioned.

Suitable operating mechanism is provided for reciprocating the bed 43 upwardly and downwardly. This mechanism may include a suitable electric motor 80 controlled from a control panel 81, the motor driving a belt 82 running over a pulley 83 fixed to a shaft 84, which shaft also has, accessible at one side of the machine, a hand wheel 85 by which the shaft may be turned slightly when desired, for adjusting the machine or bringing it exactly to any predetermined position. A pinion 86 is also fixed to the shaft 84 and meshes with a gear 87 on a shaft 88. Near its periphery this gear carries a crank pin 89 on which is mounted the lower end of a link 90, the upper end of which is pivoted at 91 to a bracket near the lower edge of the bed 43. Thus, as the gear 87 turns, the link 90 will move the bed 43 upwardly and downwardly along the guiding rails 42.

On the opposite side of the link 90 from the gear 87 is a fly wheel 93 mounted on a shaft 94 concentric with the shaft 88. A crank pin 89 extends from the gear 87 through the link 90 and into the fly wheel 93, so that the gear and fly wheel turn with each other. The fly wheel is suitably counter-weighted to compensate for the mass of the link 90, or a separate counterweight 95 may be provided on the shaft 88 if preferred.

To hold the sheets of stock to be printed, and to bring them into cooperative relationship with the printing portions 57 and 58, there is provided an impression roller 100 freely rotatable upon a shaft 101, the ends 102 of which shaft are of reduced diameter, and arranged eccentrically with relation to the intermediate portion of the shaft on which the impression roller 100 turns. These eccentric ends 102 extend through eccentric bushings 103 mounted in suitable openings in the frame 41. The bushings 103 may be turned in the frame to adjust the entire shaft 101 bodily toward and away from the type portions 57 and 58, and when properly adjusted may be locked against further turning by suitable means such as the set screws 104. The shaft 101 may itself be turned in the bushings 103 by means of a crank arm 105 keyed to one end of the shaft by a key 106 as shown especially in Fig. 7. Such turning of the shaft 101 will throw the central portion of the shaft on which the roller 100 rotates closer to or farther away from the vertical plane

of the printing portions 57 and 58 due to the fact that this central portion of the shaft is eccentric with respect to its ends 102. Thus, by suitable manipulation of the crank arm 105, the roller 100 may be brought into proper cooperative printing relationship to the printing portions 57 and 58 during movement of these printing portions in one direction (such as downward movement thereof) and may be moved slightly back away from the plane of the printing portions to be out of cooperation therewith during movement of the printing portions in the opposite directions (such as during upward movement of the printing portions).

Suitable mechanism is provided for moving the crank arm 105 at the proper times to accomplish this movement of the roller 100 toward and away from the plane of the printing portions 57 and 58. For instance, the shaft 88 may be provided with a box cam 110 (Figs. 2 and 4) in which runs a cam follower roller 111 mounted on one arm 112 of a bell crank lever pivoted at 113 to the frame of the machine. The other arm 114 of this bell crank lever is pivoted to a link 115 which extends upwardly at one side of the machine and is connected, through suitable intermediate mechanism indicated in general at 116, to a rod 117 which is pivoted to the crank arm 105. The intermediate mechanism 116 above mentioned is mechanism for breaking the connection or rendering it inoperative whenever no sheet of paper is in proper position to pass onto the impression roller 100, and this mechanism may be of any suitable conventional or known form, forming no part of the present invention. Assuming that a sheet of paper is properly positioned upon the impression roller, and that the intermediate connecting mechanism 116 is therefore not moved to an inoperative position, the crank arm 105 will be oscillated back and forth in accordance with the movement of the cam follower roller 111 in the cam 110, and this cam is so designed that at the beginning of a downward movement of the bed 43 which carries the chase 51, the shaft 101 will be turned to shift the impression roller 100 toward the plane of the printing portions 57 and 58, into cooperative printing relationship therewith, and approximately at the lower end of the movement of the bed 43, the crank 105 will be oscillated in the reverse direction to shift the roller 100 away from the plane of the printing portions 57 and 58, so that the sheet of stock on the roller will be out of contact with the printing portions when the type or printing plates move upwardly.

The cylinder 100 is provided with suitable sheet gripping means. For example the cylinder may have a longitudinal groove 120 (Figs. 7 and 12) therein, for receiving a gripper assembly comprising the plates 121 and 122 (Fig. 12) spaced from each other. Two or more grippers 123 lie between the plates 121 and 122 and are pivoted on pivot pins 124 extending into one or preferably both plates. The grippers 123 have small lugs 125 which extend laterally and overlie the top edge of the plate 121. Springs 126 (Figs. 7 and 8) normally tend to move the grippers 123 downwardly so that the lugs 125 will clamp firmly upon the edge of a sheet 127 (Fig. 12).

A bar 129 slidably between the bars 121 and 123 on guide pins 130 has cam portions 131 (Figs. 7 and 8) which, when the bar is moved rightwardly, shove up on the left hand ends of the grippers 123 and move the lugs 125 thereof upwardly as shown in Fig. 8, to release the sheet 127 or to provide space for receiving a new sheet. Plunger 75

133 pressed leftwardly by a spring 134 constantly tends to move the release bar 129 leftwardly and thus to permit the grippers 123 to move to gripping position under the influence of their springs 126.

5 Sharp pins 140 (Fig. 12) project obliquely into the groove 120 in which the paper gripping assembly is placed. When this gripping assembly is removed from the groove or slot 120, one end of a backing sheet 141 of paper or other suitable material may be forced over the pins 140 and held thereby, and the sheet 141 may then be passed around the corner of the groove 120, and around the periphery of the roller 100, and back into the opposite side of the groove 120, as plainly 10 shown in Fig. 12. Then if the gripper assembly 15 is forced back into the groove, it will frictionally retain the end of the sheet 141 in place. This backing sheet may be renewed as frequently as necessary upon removing the gripping assembly 20 from its groove or slot.

25 When the gripper assembly is in place in its slot, it is held in place therein by rings 145 extending circumferentially around the cylinder 100 in circumferential grooves formed therein near the ends of the gripper assembly, these rings 145 being each split at one point so that when they are rotated to aline the split points with the gripper assembly the gripper assembly may be removed from its slot.

30 A plunger 150 (Figs. 7 and 8) is mounted coaxially with the gripper control bar 129 at the left hand end thereof, and normally projects leftwardly from the left end of the cylinder 100, as shown in Fig. 7. Rightward movement of the 35 plunger 150 will press rightwardly upon the control bar 129 and release the grippers. To operate this plunger for releasing the grippers at the desired time, there is provided a flat annular plate 152 mounted on a pair of rods 153 which extend 40 through suitable openings in the frame 41 and which are connected to each other at their left hand ends by a bracket 154. Coiled springs 155 surrounding the rods 153 between the frame 41 and the bracket 154 normally press leftwardly 45 on the bracket and thus tend to retract the rods 153 and the plate 152 to the position shown in Fig. 7, in which the plate 152 is not pressing against the plunger 150, and the grippers 123 are in closed or gripping position.

50 In order to move the plate 152 rightwardly at the desired time to release the grippers 123, the shaft 88 previously mentioned is provided with a pinion 160 (Figs. 1, 2, and 4) which meshes with a gear 161 fixed to a stub shaft 162. Also mounted on this shaft is a cam 163 which operates upon a follower roller 164 on a lever 165 pivoted to the frame of the machine at 166. The lever is also pivoted at 167 to a link 168 which extends upwardly and is connected at its upper end (Fig. 2) 55 to one arm 169 of a bell crank lever pivoted on the frame of the machine. The other arm 170 of the bell crank lever is pivoted to a horizontal link 171 extending leftwardly to a point near the left hand side of the machine (Figs. 2 and 3) where it is pivoted to one end of a lever 172 60 mounted on a fixed pivot 173. Near its other end the lever 172 is pivoted at 174 (Figs. 3, 7, and 8) to the bracket 154. At the proper time, the cam 163 moves the follower roller 164 downwardly, 65 which pulls the link 168 downwardly, moves the link 171 leftwardly, and turns the lever 172 to shift the bracket 154 rightwardly to bring the plate 152 against the end of the plunger 150 and shove this plunger rightwardly to release the grippers 70 as indicated in Fig. 8.

The same lever 172 also controls the paper stripping mechanism, best seen in Figs. 5 and 6. Two or more stripping fingers 180 are fixed to a cross shaft 181 which is mounted parallel to the axis of the roller 100. Near the left hand end of this shaft 181 is fixed a control arm 182 which overlies a control bar 183 (Figs. 5, 6, 7, and 8) which is pivoted at 184 to the lever 172 above mentioned. When the lever 172 is moved by the cam 163, the stripper control bar 183 will be moved longitudinally, or in a direction axially of the cylinder 100. This control bar is provided with a deep notch 186 at one point, and rightwardly thereof is provided with a shallower notch 187, and still rightwardly of this notch is provided with a portion 188 of full depth or thickness, these three portions 186, 187, and 188 being connected to each other by inclined or sloping surfaces constituting cams. At the proper point in the rotation of the impression roller 100 the cam 163 operating upon the follower roller 164 moves the lever 172 to shift the control bar 183 all the way to the right, to a point where the deep notch 186 of the control bar is aligned with the control arm 182 on the shaft 181. The arm 182 then drops to the full depth permitted by this notch, bringing the sharp corners or pointed ends 190 on the strippers 180 momentarily into contact with the roller 100, just as the forward or advancing edge of the sheet of stock on this roller reaches the stripping mechanism, and just at the instant that the grippers 123 are released. The advancing edge of the paper is thus caught by the points 190 of the stripper 180 and moved outwardly 30 away from the roller 100, to strip the sheet from the roller. Almost immediately, after an extremely brief time interval, the cam 163 allows the follower roller 164 to move upwardly very slightly, so that the control member 183 is moved leftwardly by a slight amount, sufficient to remove the deep notch 186 from underneath the arm 182 and place the slightly shallower notch 187 underneath this arm. This movement of the follower roller 164 and associated parts is not sufficient, however, to cause the grippers 123 to close again, these grippers still being held open. The positioning of the slightly shallower notch 187 beneath the arm 182 causes this arm to be moved slightly in a counterclockwise direction when viewed as in Figs. 5 and 6, moving the points 190 of the strippers 180 very slightly away from the periphery of the roller 100 by a few thousandths of an inch, so that the points of the strippers will not actually bear upon the surface of the roller and will not catch thereon or cause wear on the roller during continued rotation thereof. Then, when the stripping of the sheet has been completed and when a new sheet has been brought into effective position with relation to the open grippers, the cam 163 allows the follower roller 164 to rise still higher to the uppermost limit of its travel, which again shifts the lever 172 further leftwardly, closes the grippers 123, and moves the stripper control bar 183 to bring the high point 188 thereof under the arm 182, shifting this arm further in a counterclockwise direction (Figs. 5 and 6) to move the strippers 180 entirely away from the roller 100 to their normal non-stripping position shown in Fig. 5. The shape of the cam 163 is designed to accomplish the movements above described, but the extent of movement required to shift the deep notch 186 out from under the arm 182 and place the slightly shallower arm 75

187 under this arm is so slight that the configuration of the cam 163 which accomplishes this is practically imperceptible in the drawings.

A contact roller 200 (Fig. 5) mounted on arms 5. 201 pivoted to the frame is urged by springs 202 in a direction toward the impression roller 100, to tend to keep the sheet of stock wrapped around this impression roller in proper relationship thereto and to prevent the trailing end 10 thereof from flapping loosely.

Suitable mechanism is provided for turning the impression roller 100 at the proper times and to the proper extent. In its preferred form, this means comprises a rack 205 (Figs. 2, 3, and 11) 15 mounted on and movable with the bed 43, and meshing with a gear or pinion 206 (Figs. 3, 7, 8, and 11) freely rotatable upon a leftward extension of the right hand bushing 103, and located adjacent the right hand end of the impression cylinder 100. Mounted at one point in this gear 206 is a plunger 207 constantly urged leftwardly 20 by a spring 208. The plunger acts as a clutch pin and is adapted to engage in one or another of three radial notches 209 in the right hand 25 end of the impression cylinder 100, which notches are arranged at 120° apart, as shown in Fig. 10. When viewed endwise as in Fig. 10, each notch has a straight perpendicular or abutment like side on the clockwise edge of the notch, and a beveled or oblique side at the counter-clockwise edge of the notch. As the gear 206 is turned in a clockwise direction when viewed from the right hand end of the assembly, as in Figs. 10 and 11, the pin 207 will engage in the first notch 30 209 which it comes to, and, being unable to jump past the shoulder or abutment at the clockwise side of that notch, it will form a driving connection between the gear and the cylinder 100, so that the cylinder 100 will move with the gear 40 in a clockwise direction. When the gear 206 is rotated in a counter-clockwise direction, however, the pin 207 will ride up the inclined counter-clockwise side of each notch 209 and will not turn the cylinder 100.

To prevent accidental counter-clockwise turning of the cylinder 100, which might be caused by the friction of the pin 207 thereon, the periphery of the cylinder is provided near its right hand end with three notches 211, spaced approximately 120° apart, as shown in Fig. 9, and a dog 212 has a hooked end to cooperate with these notches to prevent counter-clockwise rotation of the cylinder. The dog 212 is mounted for oscillation on a fixed shaft 213, and a spring 214 55 (Fig. 8) constantly urges the hooked end of the dog into contact with the periphery of the roller 100.

The amount of rotation to be given to the cylinder 100 at each movement of the bed 43 will depend upon the manner in which printing is to be effected upon the sheets placed upon the cylinder. In the embodiment here disclosed as an example and constituting the preferred form of the invention, the sheet of stock to be printed is 60 divided into three areas which are so arranged with relation to each other that it is desirable to turn the cylinder 100 through one and one-third revolutions at each complete reciprocation of the bed 43. Hence, the linear extent of movement of the bed 43 in each direction of its reciprocation (which is determined by the amount of eccentricity of the crank pin 89 with reference to the shaft 88) is made equal to or very slightly greater than one and one-third times the circumference 65 of the pitch circle of the gear 206, which pitch

circle is of the same size as the effective diameter of the impression roller 100, so that the roller 100 will be turned in synchronism with the movements of the bed 43, and will have a perfect rolling action with relation to the printing plates or types, without slippage. With this arrangement, each full downward movement of the bed 43 will, through the rack 205, gear 206, and clutch pin 207, cause a rotation of the impression roller 100 through exactly one and one-third revolutions, 10 the rotation being in synchronism with the movements of the printing bed so that a sheet of stock gripped in the grippers 123 on the impression roller will be properly presented to the printing portions 57 and 58 to be printed therefrom. During the subsequent upward movement of the bed 43, the impression roller will be held stationary, as the clutch pin 207 will pass idly out of each of the notches 209 which it comes to during the reverse rotation of the gear 206, and the cylinder 20 100 will be held against reverse rotation by the dog or pawl 212 engaging in a notch 211 which will come just to the proper point for cooperation with the dog at the end of each rotary movement of the cylinder. 25

At the end of the upward movement of the bed 43, the gear 206 will have been turned back to its initial position and the clutch pin 207 will be just in engagement with one of the notches 209 if each movement of the bed 43 causes exactly one 30 and one-third revolutions of the gear 206, or will be just a little to the rear of one of the notches 209, if each movement of the bed 43 causes slightly more than one and one-third revolutions of the gear 206 as is preferably the case in order 35 to allow a little leeway. Then, upon the next downward movement of the bed 43, the gear 206 will again turn in a clockwise direction when viewed from the right hand end, and if the pin 207 is not already against the abutment shoulder of its associated notch 209, it will very quickly 40 come into contact with the abutment shoulder of the notch and thus form a driving connection between the gear and the cylinder. The cylinder will again be turned through one and one-third revolutions during the downward movement of the bed 43 and will be held stationary during the upward movement of the bed. 45

With this preferred arrangement, providing for turning the impression cylinder through one and one-third revolutions at each reciprocation of the printing element, it will be apparent that three printing operations, resulting in four complete revolutions of the cylinder 100, will be sufficient to print all three of the areas on the sheet of stock held on the impression cylinder. Hence, a new sheet is to be fed to the impression cylinder at every fourth revolution thereof or at every third complete reciprocation of the bed 43, and the finished sheet is likewise to be stripped from the impression cylinder at every fourth revolution thereof or every third complete reciprocation of the bed 43. The gears 160 and 161 therefor have the required sizes and number of teeth so as to give a three to one reduction. Thus the shaft 162, on which is mounted the cam 163 for controlling the opening and closing of the sheet grippers on the cylinder and for controlling the sheet stripping mechanism, rotates one-third as fast as the shaft 88 which controls the reciprocations of the bed 43, and the gripping and stripping mechanism will be operated once for every three printing operations. The cam 110 which controls the oscillation of the arm 105 and the movements of the cylinder 100 toward and 70 75

away from the plane of the type is mounted on the shaft 88, however, so that the proper lateral movements of the cylinder 100 will take place at each printing operation.

5 At 225 is shown a fragment of a conventional sheet feeding mechanism of any suitable kind, such as is commonly available on the market. This feeding mechanism delivers sheets of stock one at a time onto the belts or tapes 226 running over rollers 227, 228, 229, and 230. The belts or tapes are driven by means of gear teeth 232 secured to the roller 227 and meshing with gear teeth 233 operatively connected to a sprocket 234 driven by a chain 235 from a sprocket 236 on a shaft 237, which shaft, in turn, is driven by a sprocket 238 fixed to the shaft, and over which runs a driving chain 239 driven by a sprocket 240 fixed on the shaft 162. The feeding mechanism 225 itself is driven in any suitable manner, as, for example, from the gear 233, and is so timed that it delivers one sheet to the belts or tapes 226 for each three reciprocations of the bed 43 or each four revolutions of the impression cylinder 100.

20 The belts 226, in running from the roller 227 toward the impression cylinder 100 pass first over a substantially horizontal table 245, and then over a table or shelf 246 inclined slightly downwardly toward the top edge of the impression cylinder, as readily seen in Fig. 4.

25 30 A sheet stop comprising one or more members 250 is moved into position to contact with the advancing edge of the sheet on the belts 226 and momentarily stop the movement of the sheets when the advancing edge of each sheet is approximately at the junction between the horizontal table 245 and the inclined shelf 246. When the sheet is stopped, a clamping bar 252 is moved downwardly onto the sheet to hold it firmly along a line substantially parallel to and spaced inwardly from the left hand edge of the sheet. The clamping bar 252 may be mounted on studs 253 projecting upwardly from the bar into suitable holes in a stationary frame 254, and springs 255 overlying the upper ends of the studs 253 constantly press downwardly on these studs and tend to depress the clamping bar 252.

35 40 A shaft 257 journaled in suitable openings in the frame 254 passes close to the studs 253 and is provided with a notch forming an abutment 258 which underlies and cooperates with an abutment 259 on each stud 253. An operating arm 260 is fixed to the shaft 257 and has a rounded end overlying the rounded end of another arm 261 pivoted to the frame at 262 and operated by a link 263 having on its lower end a bracket 264 which is forked and which embraces the shaft 237 to be guided thereby. The bracket 264 carries a follower roller 266 riding on the periphery of a cam 267 fixed to the shaft 237. During a considerable part of each revolution of the shaft 237 the cam 267 holds the follower roller 266 and the link 263 in its uppermost position, which elevates the arms 261 and 260 and holds the shaft 257 in such position that the abutment 258 holds the studs 253 in an elevated position against the tension of the springs 255, thus maintaining the clamping bar 252 in the position shown in Fig. 14, so that the sheet of stock indicated at S is not clamped. When the paper stop 250 has been moved to an effective position by mechanism controlled from the shaft 237 or in any other suitable way, and the sheet S has come into contact with and been stopped by this stop 250, then the cam 267 allows the follower roller 266 and the link 263 to move downwardly, permitting the

5 arms 261 and 260 to move downwardly and allowing the springs 255 to press the clamping bar 252 down into clamping engagement with the sheet S.

10 Another cam 270 on the shaft 237, preferably a box cam, actuates a follower roller 271 mounted near the lower end of a link 272. The upper end of this link is pivoted at 273 to an arm 274 which is fixed to a shaft 275 near one end thereof. Near the other end of the shaft is another arm 276. Links 278 and 279 pivoted to these arms 274 and 276, respectively, extend upwardly therefrom and carry at their upper ends a crimping bar 280 which has a channel 281 formed along its right hand edge in position to receive the 15 left hand edge of the sheet S, as shown in Fig. 14. Studs 283 extend loosely into openings in the bar 280 and in the frame 41, and are surrounded by coiled springs 284 which constantly tend to move the bar 280 rightwardly against the clamping bar 252, but allow it to spring back away from the bar when necessary.

20 25 The box cam 270 is so shaped that while the clamping bar 252 is in its effective clamping position, the link 272 will first be raised to move the crimping bar 280 upwardly to the position shown in Fig. 15, and then will be lowered to move the crimping bar down to the position shown in Fig. 16, after which the crimping bar will be returned to its normal intermediate position shown in Fig. 30 35 14, and the clamping bar 252 will be released. At about this same time the stop 250 is withdrawn and the sheet S is once more moved ahead by the constantly running belts or tapes 226.

40 45 The upward and downward movements of the crimping bar 280 causes the sheet S to be crimped or creased along the line of the left hand edge of the clamping bar 252. At the uppermost limit of motion of the bar 280, the lower side wall of the channel 281 is moved to a position just above the original normal plane of the sheet S, as plainly shown in Fig. 15, so that the sheet is bent upwardly around the corner of the clamping bar 252, the springs 284 allowing the crimping or 50 55 accommodate the thickness of the paper interposed between the parts 280 and 252 so that the action is a creasing one rather than an actual cutting or shearing one. Similarly, when the crimping or creasing bar 280 is moved downwardly to the lowermost position shown in Fig. 16, the upper side wall of the channel 281 is just below the normal undeflected plane of the sheet S, so the sheet is necessarily bent downwardly as plainly shown in Fig. 16, creasing it in the 60 65 opposite direction along the same line coincident with the left hand edge of the clamping bar 252. When this crimping or creasing operation is completed the sheet will have a well defined crease substantially parallel to and spaced slightly inwardly from its left hand edge, so that if a number of sheets be bound together along their left hand edges to form a book (such as a check book or the like) the crease in each sheet will enable the sheet to bend more readily and the sheets 65 70 75 may thus be opened up more easily into a substantially flat condition than would be the case if this creasing were not provided.

When the paper stop 250 is withdrawn, the sheet advances down the inclined table 243 and 70 75 comes to rest against a second paper stop (not shown) which may be of any conventional or known form, just in advance of the impression cylinder 100. Then this stop is withdrawn while the impression cylinder 100 is stationary during 75

the upward movement of the printing element 43 immediately after the completion of all three printing operations upon the immediately preceding sheet of stock. Upon the withdrawal of this second paper stop, the sheet advances to the grippers 123, which are now open and are at the top of the cylinder, in position to receive the advancing edge of the sheet. The immediately preceding sheet has been partially but not yet 10 fully stripped from the cylinder 100. Near the upper end of the upward movement of the printing element 43 the grippers 123 will be closed upon the fresh sheet which has just arrived at the cylinder 100, and during the next downward movement of the printing element 43, the cylinder 100 will be turned, effecting the first of the three printing operations upon the fresh sheet now gripped on the cylinder, and the first 15 part of this turning of the cylinder 100 will complete the stripping of the previously printed sheet from the cylinder, which stripped sheet will fall onto any suitable receptacle, such as the shelf 300 (Figs. 1 and 4).

In Figs. 23, 24, and 25, there are shown three successive stages in the printing of a typical sheet 310 designed to carry three printed areas, each consisting of a check and its associated stub. The crimped or creased line formed by the mechanism illustrated in Figs. 14, 15, and 16, is shown 25 diagrammatically at 311. In the illustrative example here given, the name of the bank appearing on each check, and the consecutive or serial number appearing on each check and the corresponding stub, are printed in one ink, such as red 30 ink, by type or a printing plate in the location 58, near the lower edge of the chase 51, the red ink being supplied by the inking mechanism 68. The other matter on each check and stub area, such as the name of the issuing company, the word- 35 ing "pay to the order of," the usual text on the stub, etc., is printed in a different ink, such as black ink supplied by the inking mechanism 61, the type or printing plate for printing this matter being located at 57 near the upper edge of 40 the chase 51.

In the preferred form of construction, the impression cylinder 100 is made of such size that its circumference is substantially equal to, or 45 very slightly greater than, the dimension of the sheet in the direction across all three areas to be printed. In other words, when the forward edge of the sheet (that is, the top edge when viewed as in Figs. 23 to 25) is gripped in the grippers 123, and when the impression cylinder is turned 50 so that the sheet becomes wrapped around the circumference of the cylinder, the rear or trailing edge of the sheet will be very close to or substantially in contact with the forward or advance edge of the sheet, the sheet thus being wrapped 55 around substantially the entire circumference of the cylinder.

Upon the first downward movement of the printing element 43 and the accompanying rotation of the impression cylinder 100 through one 60 and one-third revolutions, the printing portion 58 will print the red matter on the first check and stub area and the printing portion 57 will print the black matter upon the third check and stub area, nothing being printed at this time 65 upon the intermediate or second check and stub area. The appearance of the sheet at the end of this first printing operation will be that indicated in Fig. 23.

Due to the fact that in the first printing operation the impression cylinder was turned at one

and one-third revolutions, the cylinder will start the second printing operation a third of a revolution around from the position in which it started the first printing operation. Hence, during the second downward movement of the printing element 43, the red printing portion 58 will print the red matter a third of a revolution farther around the cylinder from the position in which it was printed in the preceding printing operation. Thus, the red matter will be printed 10 on the second check and stub area. Likewise, the printing portion 57 will print the black matter in a position a third of a revolution around the impression cylinder from that in which the black matter was printed in the previous printing operation so that the black matter will now be printed on the first check and stub area, this being a third of a revolution around the cylinder from the last or third check and stub area previously printed. At the end of this second printing operation, the appearance of the sheet will be as indicated in Fig. 24. The first check and stub area has now been entirely completed with both red and black printing. The second area has been printed only in red but not in black, 20 and the third area has been printed only in black but not in red.

Due to the rotation of the impression cylinder 100 through one and one-third revolutions, at the time of the second printing operation, this cylinder will start the third printing operation a third of a revolution farther around than the position in which it started the second printing operation. Hence, the respective red and black printing will each take place on areas a third 30 of a revolution around from those printed upon during the preceding operation. Thus, during the third printing operation, the printing portion 58 will print the red matter on the third check and stub area, while the printing portion 57 will print 35 the black matter on the second check and stub area. The appearance of the sheet at the end of this third printing operation is indicated in Fig. 25, and it will be seen that at this time all 40 three of the areas have been printed with both 45 inks, so that the entire sheet is now finished.

The printing portions 57 and 58 may each be said to print substantially the same matter upon each area of each sheet, but it is obvious that some slight changes in the exact matter printed 50 may be made from time to time, either by manually changing the type matter upon stopping the machine at the proper time, or by automatic changes in the type matter. For example, one or 55 the other of the printing portions may carry one or more numbering heads of known construction, as commonly used in the printing art, for printing the consecutive or serial numbers upon the checks and the stubs. At each printing operation, the numbering heads are advanced one unit, 60 so that the number printed thereby is one higher than the number previously printed. In the example here illustrated, two such numbering heads are employed, one for printing upon the check and one for printing upon the stub portion 65 corresponding thereto, and each of these numbering heads is included in the printing portion 58 rather than in the portion 57, since it is desired to print the numbers in red.

A brief review of the operation of the machine 70 as a whole will now be given. The paper feeding mechanism 225 feeds sheets one at a time onto the constantly moving belts or tapes 226. The stop 250 is positioned in the path of travel of the sheet, so that when the advancing edge of the 75

sheet reaches the stop, further travel of the sheet is prevented even though the sheet still rests upon the traveling belts 226. The clamping bar 252 now moves downwardly and clamps the sheet 5 near its left hand edge, leaving a margin projecting leftwardly beyond the clamping bar as shown in Fig. 14. The cam 270 then moves the crimping or creasing bar 280 upwardly to the position shown in Fig. 15, and then downwardly to the 10 position shown in Fig. 16, and then back up to its intermediate position shown in Fig. 14. The upward and downward movements of the creasing bar cause a creasing of the sheet along a line 311 (Figs. 23, 24, and 25) near the left hand edge 15 of the sheet, so that when the sheets are bound into a check book, the book may be opened more easily.

The clamping bar 252 is now released by the cam 267, and the stop 250 is withdrawn. The 20 withdrawal of the stop permits the sheet to advance once more under the influence of the moving tapes 226 so that the sheet moves off of the horizontal table 245 onto the inclined table 246, and the advancing edge of the sheet comes 25 against and is stopped by the second paper stop (not shown). Upon the withdrawal of this stop, in proper timed relation to the other movements, the sheet advances through the slight remaining distance between the second stop and the impression cylinder, and reaches the impression cylinder 100 at a time when the impression cylinder is stationary and when the grippers 123 on this cylinder are at the uppermost part of the cylinder (substantially tangent to the table 246) and are 30 open to receive the new sheet. At this time, the printing element 43 is in process of moving upwardly toward the upper limit of its motion.

Just before the upward limit of motion of the printing element 43 is reached, the cam 163 acting 40 upon the follower roller 164 moves the connections 168, 171, 172 to shift the plate 152 leftwardly from the position shown in Fig. 8 to the position shown in Fig. 7, thus closing the grippers 123 so that the portions 125 thereof grip firmly 45 upon the finished sheet which has just been delivered to the cylinder 100. At the end of the upward movement of the printing element, the clutch pin 207 mounted in the gear 206 snaps into or is positioned just behind one of the 50 notches 209 in the right hand end of the cylinder 100 ready to drive the cylinder when the gear 206 commences to rotate in the opposite direction.

The parts are now substantially in the position 55 illustrated diagrammatically in Fig. 17. As the rotation of the gear 87 continues, the link 90 begins to pull the printing element 43 downwardly. The downward movement of the printing element drives the gear 206 through the rack 205, 60 and the rotation of the gear 206 is transmitted through the clutch pin 207 to the cylinder 100 causing this cylinder to rotate in a clockwise direction when viewed from its right hand end as in Figs. 9 to 12, inclusive, or in a counter-clockwise direction when viewed from its left hand as in Figs. 17 to 22, inclusive. Since the grippers 123 are already closed upon the sheet of stock, the rotation of the cylinder carries the sheet along with it.

70 Very early in this downward movement of the printing element 43, the box cam 110 acting upon the follower roller 111, moves the links 115 and 117 to turn the arm 105 which is secured to the eccentric shaft 101 on which the cylinder 100 is 75 mounted. It will be understood that the maxi-

mum movement of the cylinder caused by shifting the eccentric shaft is relatively slight in comparison to the depth of the gear teeth of the rack 205 and the gear 206, so that the rack and gear remain properly meshed with each other at 5 all times, irrespective of the movements of the shaft 101. The turning of the shaft 101 at the beginning of the downward movement of the printing element shifts the whole cylinder 100 a slight distance bodily toward the plane of the 10 printing types, into proper impression-making or printing relationship therewith.

As downward movement of the printing element continues, the lower or red printing portion 58 comes into contact with the first area of 15 the sheet of stock, as indicated in Fig. 18, and prints on this area. Then a little later during the downward movement of the printing element, the upper printing portion 57 of the printing element comes, in turn, into contact with the sheet 20 of stock, as indicated in Fig. 19, and prints on this sheet in the third area thereof, leaving the second area unprinted for the time being.

At the completion of the downward movement 25 of the printing element 43, the first area of the sheet has been printed upon by the red printing type 58 and the third area of the sheet has been printed upon by the black printing type 57, the condition of the sheet at this time being substantially as shown in Fig. 23. Approximately at 30 the end of the downward movement of the printing element, the cam 110 again shifts the links 115, 117 to turn the eccentric shaft 101 a slight amount in the opposite direction, throwing the whole cylinder 100 bodily away from the plane 35 of the printing types 57 and 58.

Continued rotation of the gear 87 now carries the printing element 43 upwardly (Fig. 21), but during such upward movement, no printing takes place because the cylinder 100 has been 40 separated laterally a slight distance from the effective surface of the printing portions. Likewise, during such upward movement the cylinder 100 does not turn, but is held against retrograde 45 turning by the dog or pawl 212 engaged in one of the notches 211 of the cylinder, and although, the gear 206 turns backwardly, the clutch pin 207 thereof simply clicks idly past the notches 209 in the cylinder.

The printing element 43 now reaches the upward limit of its travel (Fig. 22) and starts downwardly again for a second printing operation 50 which is substantially the same as the first printing operation just described above, except that at the start of the second printing operation the cylinder 100 is a third of a revolution farther around than it was at the start of the first printing operation and except that the linkage 168, 171, 172 is not moved at this time because the grippers are already closed upon the 55 paper and are not to be released until three printing operations have been performed upon the sheet. Hence the cam 163 which controls the linkage 168 rotates only one revolution for every three revolutions of the gear 87 which moves the printing element 43 up and down. The cam 110 which controls the oscillation of the eccentric shaft 101 is effective at each printing operation, however, and at the beginning of the second printing operation, as at all of the other 60 printing operations, this cam moves the cylinder 100 into proper impression-making relationship to the printing types, and again moves the cylinder laterally away from the printing types at 65 the end of each downward movement of the 70 cylinder 100.

printing element so that the sheet will not be smeared during the subsequent upward movement of the printing element.

At the end of the second printing operation the sheet of stock has been printed to the extent indicated in Fig. 24. Then the printing element 43 moves upwardly once more and then starts to move downwardly for the third printing operation, at the commencement of which the cylinder 100 is a third of a revolution farther around than it was at the beginning of the second printing operation, or two-thirds of a revolution farther around than it was at the beginning of the first printing operation.

15 During the third printing operation, the cam 163 acts upon the follower roller 164 to move the linkage 168 at an intermediate point of the downward movement of the printing element 43, which action is preferably timed so that it takes place after the red printing type 58 has finished its printing upon the sheet, and about or a little after the time when the black printing type 57 is beginning its printing operation upon the sheet. This movement of the linkage 168 causes 20 movement of the parts 171 and 172 to shift the gripper release plate 152 rightwardly from the position shown in Fig. 7 to the position shown in Fig. 8, to open the grippers 123 just as the advancing edge of the sheet is about to reach the points 190 of the strippers 180 (Figs. 5 and 6). Simultaneously the stripper control bar 183 has also been moved rightwardly to the full limit of its motion, so that the control arm 182 is enabled to drop into the deep notch 186 of the 25 control bar, throwing the points 190 of the strippers 180 against the surface of the cylinder 100 just as the advancing edge of the sheet is about to reach these stripper points. The edge of the sheet is caught by the points 190 and forced outwardly away from the periphery of the cylinder 100. In spite of the release of the grippers 123 and the stripping of the advancing edge of the sheet from the cylinder, the final stages of the 30 printing operation, performed by the type portion 57, may nevertheless continue satisfactorily, because at this time the type 57 is in contact with the sheet and itself serves to press the sheet sufficient tightly against the cylinder to prevent slippage of the sheet on the cylinder, which holding has also been assisted by the contact roller 200.

The points 190 of the strippers 180 remain in contact with the cylinder 100 only momentarily, just long enough to catch the advancing edge of the sheet. Almost immediately, the cam 163 moves the linkage 168, 171, 172, a very slight distance in the reverse direction, not enough to close the grippers 123, but enough to shift the pawl 183 so that the control arm 182 of the grippers is now in the shallower notch 187 instead of in the deeper notch 186. This shallower notch 187 holds the points 190 of the strippers slightly away from the periphery of the cylinder 100, but still maintains the strippers in such position that they 35 form smooth guides for receiving and guiding the sheet as it comes off of the cylinder, so that the sheet will be deposited on the receiving shelf 300.

At the end of the downward movement of the printing element 43 during this third or final printing operation, the cylinder 100 comes to rest as before, but this time the grippers are open and are substantially at the top of the cylinder, ready to receive a fresh sheet, and the sheet on which the printing has just been completed remains partially stripped but not yet wholly re-

moved from the cylinder. During the upward movement of the printing element 43, the fresh sheet which has already been creased by the mechanism shown in Figs. 14, 15, and 16, and which has come down the table 246 to the second paper stop, advances upon the withdrawal of this second stop and enters the open grippers on the cylinder 100. The above described printing operation is now ready to be performed over again with reference to this fresh sheet. The first part 10 of the first downward movement of the printing element 43 for printing upon the new sheet turns the cylinder 100 far enough to complete the removal therefrom of the old sheet.

The shaft 237 may be provided with a cam 320 (Fig. 1) acting upon a follower roller 321 on an arm 322 to control any suitable or conventional known form of mechanism for moving the ink mountains away from the printing types whenever no sheet of stock is properly positioned on the impression cylinder 100. Since this mechanism for throwing out the inking mechanism may be of conventional form and constitutes no part of the present invention, it is not described in detail here.

While one embodiment of the invention has been disclosed, it is to be understood that the inventive idea may be carried out in a number of ways. This application is therefore not to be limited to the precise details described, but is intended to cover all variations and modifications thereof falling within the spirit of the invention or the scope of the appended claims.

I claim:

1. Printing apparatus comprising a printing element, an impression element for pressing a sheet against said printing element, sheet gripping means mounted on and moving with said impression element to hold a sheet on and carry it along with said impression element, one of 35 said elements being substantially in the form of a cylinder adapted to roll over the other of said elements, means for moving one of said elements relatively to the other in one direction and for simultaneously turning said cylindrical element 45 in substantial synchronism with the relative movement between them through a rotary extent substantially different from a single complete revolution, and means for moving one of said elements relatively to the other in the opposite direction without substantial turning of said cylindrical element during such opposite directional relative movement.

2. Printing apparatus comprising a printing element, an impression element for pressing a sheet against said printing element, one of said elements being substantially in the form of a cylinder adapted to roll over the other of said elements, means for inking different parts of said printing element with inks of different colors, means for moving one of said elements relatively to the other in one direction and for simultaneously turning said cylindrical element in substantial synchronism with the relative movement between them through a rotary extent substantially different from a single complete revolution, and means for moving one of said elements relatively to the other in the opposite direction without substantial turning of said cylindrical element during such opposite directional relative movement.

3. Printing apparatus comprising a printing element, an impression element for pressing a sheet against said printing element, sheet gripping means mounted on and moving with said 75

impression element to hold a sheet on and carry it along with said impression element, one of said elements being substantially in the form of a cylinder adapted to roll over the other of said elements, the other of said elements being mounted for reciprocation along a path of travel substantially tangent to said cylindrical element, means for moving said other of said elements in one direction along said path of travel and for concomitantly turning said cylindrical element at a peripheral speed substantially equal to the linear speed of movement of said other of said elements and through a rotary extent materially different from a single complete revolution, means for separating said two elements from each other laterally, and means for moving said other of said elements in the opposite direction along said path of travel while said two elements are separated from each other and without substantial turning of said cylindrical element.

4. Printing apparatus comprising a printing element, an impression element for pressing a sheet against said printing element, sheet gripping means mounted on and moving with said impression element to hold a sheet on and carry it along with said impression element, one of said elements being substantially in the form of a cylinder adapted to roll over the other of said elements, the other of said elements being mounted for reciprocation along a path of travel substantially tangent to said cylindrical element, means for reciprocating said other of said elements in both directions along said path of travel, means for inking different parts of said printing element with inks of different colors, means for turning said cylindrical element during movement of said other of said elements in one direction in substantial synchronism therewith and in pressure-exerting relationship therewith to produce a printing impression upon sheet material interposed between said two elements, the extent of turning of said cylindrical element during said movement of said other of said elements in one direction being materially greater than a single complete revolution and materially less than two complete revolutions, and means for separating said two elements laterally from each other during movement of said other of said elements in the opposite direction and for holding said cylindrical element substantially against turning during said opposite directional movement of said other of said elements.

5. Printing apparatus comprising a printing element having printing surface portions lying substantially in a plane, a substantially cylindrical impression element for pressing a sheet against said printing surface portions of said printing element, sheet gripping means mounted on and moving with said impression element to hold a sheet on and carry it along with said impression element, means for inking different printing surface portions with different inks, means for reciprocating said printing element back and forth past said impression element, means for turning said impression element in one direction substantially in synchronism with the movements of said printing element in one direction and for holding said impression element substantially against turning during the movements of said printing element in the opposite direction, the extent of turning of said printing element during a single full movement of said printing element in one direction being ma-

terially greater than a single complete revolution, and means for moving one of said elements toward and away from the other of said elements to bring them into pressure-exerting relationship to each other during at least a part of the time when said impression element is turning and to separate them from each other during at least a part of the time when said printing element is moving without turning of said impression element.

6. Printing apparatus comprising a printing element having printing surface portions lying substantially in a plane, a substantially cylindrical impression element for pressing a sheet against said printing surface portions of said printing element, means for inking different printing surface portions with different inks, means for reciprocating said printing element back and forth past said impression element, means for turning said impression element in one direction substantially in synchronism with the movements of said printing element in one direction and for holding said impression element substantially against turning during the movements of said printing element in the opposite direction, the extent of turning of said impression element during a single full movement of said printing element in one direction differing from a single complete revolution substantially by a material aliquot part of a single revolution, and means for moving one of said elements toward and away from the other of said elements to bring them into pressure-exerting relationship to each other during at least a part of the time when said impression element is turning and to separate them from each other during at least a part of the time when said printing element is moving without turning of said impression element.

7. Printing apparatus for printing the same letter press matter a plurality of times in a plurality of different positions on a single sheet of stock in a plurality of different inks, said apparatus comprising a movable printing element having a plurality of printing portions spaced from each other, means for inking one of said printing portions with one ink and another of said portions with a different ink, an impression cylinder having means for holding a single sheet of stock wrapped around substantially the entire circumference of said cylinder, operating means for moving said printing element back and forth past said cylinder and for bringing said printing element and said cylinder into cooperative impression-making relationship to each other during movements of said printing element in one direction and separating said element and cylinder from each other during movements of said printing element in the opposite direction, and means for turning said cylinder through substantially more than one complete revolution in substantial synchronism with the movements of said printing element in said one direction without turning said cylinder during movements of said printing element in said opposite direction.

8. Printing apparatus for printing substantially the same matter in a plurality of different areas of substantially the same size on a single sheet of stock in a plurality of different inks in each area, said apparatus comprising a movable printing element having one type portion for printing all of the matter to be printed in one ink in each area and another type portion for printing all of the matter to be printed in a different ink in each area, said two type portions being

spaced from each other in one direction to an extent substantially equal to the corresponding dimension of one of such areas, an impression cylinder having means for holding on the circumference thereof a sheet of stock having an area of not less than the combined area of at least three of said areas to be printed, operating means for moving said printing element back and forth past said cylinder and for bringing said printing element and said cylinder into cooperative impression-making relationship to each other during movements of said printing element in one direction and separating said element and cylinder from each other during movements of said printing element in the opposite direction, and means for turning said cylinder upon each full backward and forward movement of said printing element through a rotary extent substantially greater than one complete revolution, so that at each successive movement of said printing element in said one direction a different pair of areas of said sheet of stock to be printed upon will be presented to said two type portions.

9. Printing apparatus for printing substantially the same matter in a plurality of different areas of substantially the same size on a single sheet of stock in a plurality of different inks in each area, said apparatus comprising a movable printing element having one type portion for printing all of the matter to be printed in one ink in each area and another type portion for printing all of the matter to be printed in a different ink in each area, said two type portions being spaced from each other in one direction to an extent substantially equal to the corresponding dimension of one of such areas, an impression cylinder having means for holding on the circumference thereof a sheet of stock having an area of not less than the combined area of at least three of said areas to be printed, operating means for moving said printing element back and forth past said cylinder and for bringing said printing element and said cylinder into cooperative impression-making relationship to each other during movements of said printing element in one direction and separating said element and cylinder from each other during movements of said printing element in the opposite direction, and means for turning said cylinder upon each movement of said printing element in said one direction through a rotary extent differing substantially from one complete revolution and for holding said cylinder substantially against turning during movement of said printing element in said opposite direction, so that at each successive movement of said printing element in said one direction a different pair of areas of said sheet of stock to be printed upon will be presented to said two type portions.

10. Printing apparatus for printing substantially the same matter in three different areas of substantially the same size on a single sheet of stock in two different inks in each area, said apparatus comprising a movable printing element having one type portion for printing all of the matter to be printed in one ink in each area and another type portion for printing all of the matter to be printed in the other ink in each area, said two type portions being spaced from each other by an amount sufficient to print upon two spaced areas with one intervening area between them, an impression cylinder having a circumference substantially equal to the over-all dimension in one direction of three juxtaposed areas to be printed so that a sheet of stock hav-

ing three such areas may be wrapped around substantially the entire circumference of said cylinder with opposite edges of said sheet lying closely adjacent each other, operating means for moving said printing element back and forth past said cylinder and for bringing said printing element and said cylinder into cooperative impression-making relationship to each other during movements of said printing element in one direction and separating said element and cylinder from each other during movements of said printing element in the opposite direction, and means for turning said cylinder through substantially one and one-third revolutions for each complete forward and backward movement of said printing element, so that at each successive movement of said printing element in said one direction a different pair of areas of said sheet of stock will be presented to said two type portions until all three areas of said sheet have been printed by both of said type portions.

11. Printing apparatus for printing substantially the same matter in three different areas of substantially the same size on a single sheet of stock in two different inks in each area, said apparatus comprising a movable printing element having one type portion for printing all of the matter to be printed in one ink in each area and another type portion for printing all of the matter to be printed in the other ink in each area, said two type portions being spaced from each other by an amount sufficient to print upon two spaced areas with one intervening area between them, an impression cylinder having a circumference substantially equal to the over-all dimension in one direction of three juxtaposed areas to be printed so that a sheet of stock having three such areas may be wrapped around substantially the entire circumference of said cylinder with opposite edges of said sheet lying closely adjacent each other, operating means for moving said printing element back and forth past said cylinder and for bringing said printing element and said cylinder into cooperative impression-making relationship to each other during movements of said printing element in one direction and separating said element and cylinder from each other during movements of said printing element in the opposite direction, and means for turning said cylinder through substantially one and one-third revolutions for each complete movement of said printing element in said one direction and for holding said cylinder substantially against turning during movement of said printing element in said opposite direction, so that at each successive movement of said printing element in said one direction a different pair of areas of said sheet of stock will be presented to said two type portions until all three areas of said sheet have been printed by both of said type portions.

12. Printing apparatus for printing substantially the same matter in three different areas of substantially the same size on a single sheet of stock in two different inks in each area, said apparatus comprising a movable printing element having one type portion for printing all of the matter to be printed in one ink in each area and another type portion for printing all of the matter to be printed in the other ink in each area, said two type portions being spaced from each other by an amount sufficient to print upon two spaced areas with one intervening area between them, an impression cylinder having a circumference substantially equal to the over-

- all dimension in one direction of three juxtaposed areas to be printed so that a sheet of stock having three such areas may be wrapped around substantially the entire circumference of said cylinder with opposite edges of said sheet lying closely adjacent each other, operating means for moving said printing element back and forth past said cylinder and for bringing said printing element and said cylinder into cooperative impression-making relationship to each other during movements of said printing element in one direction and separating said element and cylinder from each other during movements of said printing element in the opposite direction, means for turning said cylinder through substantially one and one-third revolutions for each complete forward and backward movement of said printing element, and means for securing a sheet of stock to said cylinder and holding it thereon for approximately four revolutions of the cylinder and for stripping said sheet from the cylinder and securing a fresh sheet thereon near the end of four revolutions of the cylinder.

13. Apparatus for printing a plurality of forms on each of a plurality of sheets of stock and for breaking a hinge joint along a predetermined line on each sheet so that when a number of such sheets are bound together along one edge to form a book the sheets will open readily, said apparatus comprising a printing element having a type portion for printing a form, sheet carrying means, means for moving said printing element and said sheet carrying means relatively to each other to present said type portion a plurality of times to a sheet carried by said carrying means in different positions relatively to said sheet to print said form a plurality of times on each sheet, means for feeding a plurality of sheets successively to said carrying means, and mechanism operating in timed relationship to the relative movements of said printing element and said carrying means for creasing each of said sheets.

14. Apparatus for printing a plurality of forms on each of a plurality of sheets of stock and for breaking a hinge joint along a predetermined line on each sheet so that when a number of such sheets are bound together along one edge to form a book the sheets will open readily, said apparatus comprising a printing element having a type portion for printing a form, sheet carrying means, means for moving said printing element and said sheet carrying means relatively to each other to present said type portion a plurality of times to a sheet carried by said carrying means in different positions relatively to said sheet to print said form a plurality of times on each sheet, means for feeding a plurality of sheets successively to said carrying means, and mechanism operating in timed relationship to the relative movements of said printing element and said carrying means for creasing each of said sheets while each sheet is under the influence of said feeding means.

15. Apparatus for printing a plurality of forms on each of a plurality of sheets of stock and for breaking a hinge joint along a predetermined line on each sheet so that when a number of such sheets are bound together along one edge to form a book the sheets will open readily, said apparatus comprising a printing element having a type portion for printing a form, rotary sheet carrying means for carrying only a single sheet at a time, means for moving said printing element back and forth relatively to said sheet car-

rying means a plurality of times and for concomitantly turning said carrying means a plurality of times to present said type portion a plurality of times to said single sheet carried by said carrying means in different positions relatively to said sheet to print said form a plurality of times on each sheet, belt means tending to feed sheets successively toward said carrying means, a clamping member movable from an ineffective position to an effective position effective to clamp stationarily a sheet tending to be fed by said belt means toward said rotary carrying means, a creasing member having a slot for receiving the marginal edge of a sheet held by said clamping member, said creasing member being mounted for movement in a direction transverse to the plane of said sheet, and mechanism operating in timed relationship to the relative movements of said printing element and said carrying means for shifting said clamping member from said ineffective position to said effective position only once during a plurality of successive complete revolutions of said rotary carrying means and for moving said creasing member in said direction while said clamping member is in said effective position.

16. Sheet creasing and printing apparatus comprising a sheet holding member, belt means for moving a sheet toward said holding member, means for stopping said sheet at an intermediate point of its travel toward said member and for clamping said sheet along a line approximately parallel to and spaced inwardly from one edge of said sheet, leaving an unclamped margin projecting beyond said clamping means, means for bending said margin first to one side and then to the opposite side of its normal unbent position, to crease a hinge joint in the sheet, means for releasing said stopping and clamping means so that said sheet may continue its travel to said holding member, means for securing said sheet to said holding member, and type means for printing upon said sheet while it is held by said holding member.

17. Printing apparatus for printing the same letter press matter a plurality of times in a plurality of different positions on a single sheet of stock in a plurality of different inks, said apparatus comprising a movable printing element having a plurality of printing portions spaced from each other, means for inking one of said portions with one ink and another of said portions with a different ink, an impression cylinder, sheet gripping means mounted on said cylinder for holding a single sheet of stock wrapped around substantially the entire circumference of said cylinder, operating means for moving said printing element back and forth past said cylinder and for bringing said printing element and said cylinder into cooperative impression-making relationship to each other during movements of said printing element in one direction and separating said element and cylinder from each other during movements of said printing element in the opposite direction, means for turning said cylinder through one complete revolution plus a material aliquot part of a revolution during each movement of said printing element in said one direction and in substantial synchronism therewith, without turning said cylinder during movements of said printing element in said opposite direction, and means for operating said sheet gripping means to release a sheet gripped thereby only once during a plurality of reciprocations of said printing element, so that the same sheet

will remain on said impression cylinder during a plurality of reciprocations of said printing element.

18. Printing apparatus including a movable printing element mounted for reciprocation, an impression cylinder mounted for rotation in one direction in synchronism with movements of said printing element in a corresponding direction, to hold a sheet of stock wrapped on said impression cylinder in contact with printing means on said printing element during such motion in said one direction, said impression cylinder having in its periphery a groove extending in substantially an axial direction, an axially extending bar 5 movably mounted in said groove and normally held against longitudinal movement therein, a plurality of gripping dogs pivotally mounted on said bar and each having a surface for overlying a portion of a sheet wrapped on said cylinder, 10 spring means associated with said dogs to tend to move said surfaces thereof into contacting relation to said sheet to clamp said sheet on said cylinder, a cam bar also mounted in said slot and movable longitudinally therein, said cam bar having cam surfaces cooperating with said gripping dogs upon longitudinal movement of said cam bar in one direction to release said gripping dogs from said sheet against the action of said spring means, means for reciprocating said printing element and concomitantly turning said impression cylinder during reciprocating movements of said printing element in one direction, and means operating in timed relation to said reciprocations of said printing element for moving said cam bar longitudinally to release said gripping dogs from said sheet only once during a plurality of reciprocations of said printing element. 15

19. Printing apparatus including a movable printing element mounted for reciprocation, an impression cylinder mounted for rotation in one 20 direction in synchronism with movements of said printing element in a corresponding direction, to hold a sheet of stock wrapped on said impression cylinder in contact with printing means on said printing element during such motion in said one direction, said impression cylinder having in its periphery a groove extending in substantially an axial direction, said groove being undercut so as to be wider at a point radially inwardly from the surface of the cylinder than at the surface of the cylinder, a pin mounted in said cylinder and projecting into said undercut portion of said groove so that a tympan sheet may be impaled on said pin and may extend therefrom out of said groove and around the periphery of said cylinder, 25 an axially extending bar removably mounted in said groove and normally held against longitudinal movement therein, a plurality of gripping dogs pivotally mounted on said bar and each having a surface for overlying a portion of a sheet wrapped on said cylinder, spring means associated with said dogs to tend to move said surfaces thereof into contacting relation to said sheet to clamp said sheet on said cylinder, a cam bar also mounted in said slot and movable longitudinally therein, said cam bar having cam surfaces cooperating with said gripping dogs upon longitudinal movement of said cam bar in one direction to release said gripping dogs from said sheet against the action of said spring means, 30 means for reciprocating said printing element and concomitantly turning said impression cylinder during reciprocating movements of said printing element in one direction, and means operating in timed relation to said reciprocations of said printing element for moving said cam bar longitudinally to release said gripping dogs from said sheet only once during a plurality of reciprocations of said printing element. 35
